UNITED STATES PATENT OFFICE

FRANK BOOTH, OF SAN DIEGO, CALIFORNIA

IRONING APPARATUS

Application filed July 11, 1929. Serial No. 377,436.

My invention relates to ironing apparatus, and the objects of my invention are: First, to provide an apparatus of this class which may be used in connection with the conventional ironing board which folds into a cabinet built into a wall; Second, to provide an ironing apparatus which folds into the cabinet with the ironing board so as to be out of sight and out of the way when not in use; Third, to provide an apparatus of this class in which readily controlled mechanical means shift the iron about the ironing board, thereby greatly reducing the effort needed to iron; Fourth, to provide an apparatus of this class which has the ease of operation of the conventional ironing machine or mangle, yet is compact of structure; Fifth, to provide an apparatus of this class which is especially adapted for use in small homes, apartments or the like where space is limited; Sixth, to provide an apparatus of this class in which the moving parts, with the exception of the iron, are closed and concealed from view; Seventh, to provide an ironing apparatus which eliminates the need of a long, unwieldy cord connected with the iron; Eighth, to provide an ironing apparatus from which the iron may be readily and quickly removed when it is desired to use said iron in the usual manner, as when ironing delicate or difficult articles; and Ninth, to provide on a whole a novelly constructed ironing apparatus which is simple of construction proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail, and particularly set forth in the appended claims, reference being had to the accompanying drawings and to the characters of reference thereon which form a part of this application, in which:

Figure 1 is a horizontal sectional view of an ironing board cabinet, with the ironing board shown in its extended position, and with my apparatus shown in relation there-

to, partly in section and partly in plan; Fig. 2 is an enlarged transverse sectional view of my apparatus through 2-2 of Fig. 1, with parts and portions shown in elevation to facilitate the illustration; Fig. 3 is a sectional view through 3-3 of Fig. 1, showing the control knob, with parts and portions in elevation to facilitate the illustration; Fig. 4 is a sectional view through 4-4 of Fig. 3; Fig. 5 is a sectional view through 5-5 of Fig. 1, with the ironing board in elevation and with my apparatus shown fragmentarily; Fig. 6 is a sectional view through 6-6 of Fig. 1, with ironing board removed and with parts and portions shown in elevation to facilitate the illustration; Fig. 7 is an enlarged sectional view of the operating knob, taken through 7-7 of Fig. 3; Fig. 8 is a fragmentary sectional view of the traveler member and boom, taken through 8-8 of Fig. 2; Fig. 9 is another fragmentary sectional view of the terminal box and boom taken through 9-9 of Fig. 2; Fig. 10 is an enlarged sectional view of the operating mechanism taken through 10-10 of Fig. 6, with parts and portions in elevation to facilitate the illustration; Fig. 11 is a transverse sectional view of the screw and a sleeve member; Fig. 12 is a reduced sectional view through 12-12 of Fig. 10, with parts and portions removed to facilitate the illustration; Fig. 13 is a similar transverse sectional view through 13-13 of Fig. 10, with parts and portions removed and other parts and portions shown in elevation to facilitate the illustration; Fig. 14 is a transverse sectional view through 14-14 of Fig. 13; Fig. 15 is another transverse sectional view through 15-15 of Fig. 13; Fig. 16 is an elevational view of the clutch operating rings, shown in their normal relative positions; and Fig. 17 is a sectional view of the clutch operating rings taken through 17-17 of Fig. 16, with their collar member and the control rod shown in connection therewith.

Similar characters of reference refer to similar parts and portions throughout the several views of the drawings.

The hereinabove described apparatus is adapted to be mounted in a conventional

cabinet built in a wall and adapted to enclose a folding ironing board. Two guide members 1 are mounted in opposite side walls of the cabinet C of the ironing board B. A U-shaped cage member 2 is supported between the guide members 1 by its legs 2a, as shown in Fig. 6. The guide members 1 permit the cage 2 to move in a vertical plane. The extended ends of the legs 2a are provided with 10 seat portions 2b which support a screw member 3 between them, and hold said screw member against rotation.

The one end of the screw member 3 is provided with left-handed threads, while the 15 other end thereof has right-handed threads, as shown in Figs. 1, 6 and 10.

Traveler members 4 and 5 are adapted to ride on the screw member 3. The traveler members are held in spaced relation to each 20 other by sleeve members 6 and 7. The sleeve members 6 and 7 surround the screw member 3 and interlock with each other at their central portions, as shown in Fig. 10. The extended end of the sleeve member 6 increases in diameter so as to overhang a portion 25 of the traveler member 4 and provide space for a sleeve supporting bearing 8 mounted therebetween. Similarly, the sleeve member 7 is supported relative to the traveler member 5 by a bearing 9. Adjacent their interlocked ends, the sleeve members 6 and 7 are provided with drum supporting bearings 10 and 11, respectively. Cable drums 12 and 13 are mounted on the bearings 10 and 35 11 in adjacent relation to each other, as shown best in Figs. 1 and 10.

A plurality of spacers 14, in the form of collars, surround the sleeve members 6 and 7 and hold the bearings 10 and 11 in proper 40 relation. Between the enlarged extended end of the sleeve member 6 and the spacer member 14 at the outer side of the bearing 10, the sleeve member 6 is provided with a fluted portion 6a. The traveler member 4 is provided with an annular, belled out portion 4a which extends over the fluted portion of the 45 sleeve member 6, in spaced relation thereto, as shown in Fig. 10. This belled portion is provided with an internally fluted portion 4b.

50 A disk clutch means 15 links the sleeve member 6 with the traveler member 4. The clutch means consists of a plurality of driving disks 15a interlocked with the fluted portion 6a of the sleeve member 6, and driven 55 clutch plates 15b interlocked with the fluted portion 4b of the traveler member 4, and spaced apart from each other by the clutch plates 15a.

The outer side of the drum 12 is enlarged 60 and provided with an internally fluted portion 12a, which overhangs the fluted portion 6a of the sleeve member 6. The multiple disk clutch, similar to the clutch 15, connects the drum 12 with the sleeve member 6. Surrounding the space between the traveler mem-

ber 4 and the drum 12, and overhanging their margins, is a collar member 17. The collar member 17 is provided with a plurality of spaced apart, radially positioned, inwardly projecting rollers 18 which extend into the 70 space between the drum 12 and traveler member 4.

Mounted between the one side of the rollers 18 and the traveler operating clutch 15, is a clutch thrust ring 19, which is shown in Figs. 10, 16 and 17. The clutch thrust ring 19 is provided with a plurality of spaced apart cam portions 19a which join the plate at its periphery and extend axially toward alternate rollers 18, so as to be engaged thereby. 75 Each cam 19a is in the form of an inclined plane so that the rotation of the clutch thrust ring in one direction causes it to move away from the rollers 18 and to bring the several clutch plates of the clutch 15 into contact, 80 and thereby link the traveler member 4 with the sleeve member 6. For reasons to be brought out hereinafter, each cam 19a is provided with a flat portion 19b intermediate its ends, upon which the rollers 18 rest when 85 the clutch thrust ring 19 is in its normal or unengaged position.

A drum clutch thrust ring 20 is positioned between the rollers 18 and the drum clutch 16. The thrust ring 20 is similar in construction to the thrust ring 19, it being provided with axially extending cam portions 20a, having flattened portions 20b intermediate their ends. These cams 20a engage the rollers 18 not engaged by the cams 19a. Between the 90 cams 19a and 20a the thrust plates 19 and 20, respectively, are notched out, as shown in Figs. 16 and 17, so that the two plates may telescope one with the other without interfering.

105 Ball bearings 19c and 20c are supported in the thrust rings 19 and 20, respectively. These ball bearings engage the inner disk of the clutches 15 and 16, respectively, so that said clutches may rotate, yet will permit the 110 thrust ring to stand still.

The clutch thrust rings are actuated by an operating rod 21. An end piece 22 is provided on the rod which forms a suitable joint with an arm member 23 extending upwardly 115 from one of the cam portions 20a through a slot 17a in the collar 17. As the operating rod 21 extends transversely to the axis of the thrust ring, longitudinal movement of the rod causes a rotational movement of the 120 thrust ring 20, thereby moving the cam portions 20a along their rollers 18.

125 Adjacent the end of the operating rod 21, is secured a lever member 24, which normally extends substantially parallel with the axis of the thrust ring 19. An arm 26 extends horizontally from one of the cam portions 19a, through a slot 17b in the collar 17, and is connected to the lever 24 through a link member 25. Thus, rotation of the rod

21 causes an arcuate movement of the lever 24, and consequently shifts the thrust ring 19 about its axis so as to shift it into and out of engagement with the clutch 15. The mechanism for operating the rod 21 is described hereinafter.

29 are holding the clutches 15 and 27 in disengaged position. Movement of the thrust ring 19 in one direction further releases the clutch 15 and brings the clutch 27 into action. Movement in the other direction brings clutch 15 into action and further releases

Similarly, the flat portions 20b of the cams 20a hold both drum clutches 16 and 28 in disengaged positions, and movement of the thrust ring 20 brings either one or the other of said clutches 16 and 28 into action. 75

over this fluted portion 7a, and is provided with an internally fluted portion 5a so that a traveler clutch 27 of the multiple disk type, similar to the traveler clutch 15, links the traveler member 5 with the sleeve 7. Similarly, a drum clutch 28 links an internally fluted portion 13a of the drum 13 with the sleeve 7. The several connecting rods pass under-neath and are held in place by the spacer members 14 and by the inner races of the bearings 10 and 11. The thrust plates 29 and 30 form a part of the clutches 27 and 28 as they are keyed on the fluted portions 7a of the sleeve member 7 and revolve therewith about the axis.

The sleeve members 6 and 7 are provided with a plurality of longitudinally extending channels in their periphery. The channels of one sleeve are aline with the channels of the other sleeve, as shown in Fig. 10. In each of these channels, there is provided a traveler clutch connecting bar 31, the outer surface of which forms the continuation of the outer periphery of the sleeve members 6 and 7. The traveler clutch connecting bar extends from the thrust ring 19 to the thrust plate 29. The thrust ring 19 is provided with an annular channel 19d formed in its inner periphery, as shown in Fig. 10, so that an outwardly extending lug 31a at the one end of the connecting bar 31 may ride thereon. The adjacent edges of the drums 13 and 13a are provided with fluted portions 5a and 13a respectively, and positioned between the peripheries of the fluted portions 5a and 13a of the traveler member 5 and drum 13, respectively, and positioned between the pulley 34 and the traveler clutch thrust plate 29, is a traveler clutch spring 35 preferably in the form of a conical coil. A similar spring 36 for the drum clutch is positioned between the pulley and the drum clutch thrust plate 30. These springs are adapted to hold the cams 19a and 20a, respectively, in engagement with the rollers 18, and as a result oppose the placing of one of the clutches in engagement and aid in placing the opposite clutch in engagement, of each set of clutches 15 and 27, 16 and 28, respectively.

The before-described mechanism is enclosed by casing members 37 and 38. The casing member 37 is supported upon the traveler member 4 by means of a bearing, preferably a ball bearing, 39. The casing 38 is similarly supported by a bearing 40 over the traveler member 5. The casing members

plate 29. Each channel in the sleeves 6 and 7 is also provided with a drum clutch connecting bar 32, having a lug 32a at its one end adapted to ride in a groove 20d formed in the periphery of the drum clutch ring 20, and another lug 32b formed in the other end thereof adapted to ride in the groove 30a, formed in the inner periphery of the drum clutch thrust plate 30. Thus movement of the thrust ring 19 causes the corresponding movement of the thrust plate 29. Similarly, the movements of the thrust ring 20 and thrust plate 30 are linked together by the connecting bar 32.

The traveler member 3. The casing members 37 and 38 extend toward each other and telescope, the casing 38 extending along the inside of the casing 37. The casings are secured together by set screws 41 which extend into a groove 38a provided in casing 38, thus permitting the casing 37 to revolve relative to the casing 38, as shown in Fig. 10.

Extending downwardly from the casing 38, in alignment with the pulley 34, is a belt casting 42, which also forms a hanger for supporting an electric motor 43 having a drive pulley 44 thereon, adapted to fit within the

Thus when the rollers 18 are engaged by the flat portion 19b of the thrust ring 19, both the thrust ring 19 and the thrust plate 165 are moved toward the center of the belt casing 42. A belt extends around the pulley 44 and the driven pulley 34, as indicated by the dotted lines in Fig. 6.

The hangar 42 is provided with a bifurcating 130

cated, downwardly extending lug 42a between the members of which, by means of a pin 45, is mounted a trolley member 46 which rides on a track 2c formed on the cross member 2 of the cage, as shown best in Figs. 5 and 6.

Extending outwardly and preferably integral with the casing 37 is an iron supporting boom 47. This boom comprises two tubular guide portions 47a and 47b connected together at their upper sides by a ridge portion 47c. The extended ends of the tubular portions 47a and 47b merge into a pulley housing 47d in which is mounted a pulley 48. At the secured end of the boom 47 the tubes 47a and 47b intersect the casing 37, as shown in Fig. 12. Below the boom 47, adjacent to the casing 37, is another pulley housing 47e, in which is mounted a pulley 49.

A cable 50 is adapted to extend from the tube 47a around the drum 12, one or more times, around the idler pulley 49, back around the other drum 13, then out the tube 47b, around the second idler pulley 48 at the extended end of the boom and back to the tube 47a.

A channel 47f is formed in the boom 47 adjacent the tube 47b. The channel is between the tubes 47a and 47b and is open upwardly towards the ridge 47c, as shown best in Figs. 2 and 14. A track member 51 formed of insulating material is positioned in this channel 47f. The track member 51 is provided with two parallel disposed longitudinally extending grooves in each of which fits a contact bar 52.

The tube 47a is provided with a slit extending longitudinally therewith adjacent to and under the web 47c.

A traveler member 53 is provided. The one side portion 53a of the traveler member 53 is cylindrical and conforms to the shape of the tube 47a. A longitudinally extending bore 53b projects through said cylindrical portion 53a, as shown best in Fig. 8. The one end of this bore 53b is closed by a cap or anchor member 54, to which is secured one end of the cable 50. The other end of the bore 53a is closed by a collar member 55 adapted to receive a rod 56, the outer end of which is secured to the other end of the cable 50. The inner end of said rod extends through the collar into the bore 53a, and terminates in an enlarged head portion 56a. A spring 57 is positioned between this enlarged head of the rod and the collar 55. The spring tends to maintain the tension on the cable 50.

From the tubular or cylindrical portion 53a of the traveler member, said traveler member extends under the ridge 47c, then downwardly and underneath the portion of the boom forming the channel 47f. The traveler member is held in spaced relation to the boom by a plurality of small bearing

members 58, as shown best in Fig. 2. The one set of bearing members bear against the ridge portion 47c, while the other set of bearing members bear against the under side of the channel 47f, as shown in Fig. 2. Substantially centered relative to the traveler member, there is provided a downwardly extending shank portion 53c which has an opening 53d therethrough.

Secured to the traveler member so as to extend over the track member 51 is a terminal box 59, in which is mounted two terminals 60, one adapted to ride on each contact bar 52, as shown best in Figs. 2 and 9.

Pivotedly mounted upon the shank portion 53b of the traveler member is a yoke member 61 which is substantially U-shaped with downwardly extending leg portions 61a, each of which is provided with a slot in its extended end, bifurcating it, as indicated in Fig. 2. The yoke member 61 is adapted to fit across the opposite ends of a handle H of the conventional electric iron I. In place of the usual bolt and nut or screws for holding the handle H to the iron I, lock members 62 are provided, which extend into the bore H1 in the handle from opposite ends thereof and are held in relation to each other by springs 63. The outer ends of the lock members 62 are provided with head portions 62a which fit on the outside of the yoke 61 when the stem of the lock fits in the slots 61b, as shown in Fig. 2. Lugs 62b, provided on the inner face of each head portion 62a, fits in holes, not shown, positioned on opposite sides of the slots 61b in the yoke 61, so that the iron is firmly secured to said yoke member 61.

Wires W extend from the terminals 59, through the opening 53d to a conventional ironing plug P which connects the terminals with the iron in the usual manner. The wires W need not be very long as the iron is always in about the same relation to the terminal block. The friction of the joint between the yoke 61 and the shank 53c holds the iron in any desired position, but is loose enough to permit the operator to twist the iron so as to face the desired direction.

Secured in spaced relation and extending longitudinally with the iron supporting boom 47 is a control rod casing 64 which extends up to and joins the casing 37. The control rod 21 extends through the casing 64 to the extended end of the iron supporting boom 47, where it is provided at its extreme end with a collar portion 65. A knob 66, having a bore 66a therethrough, fits over the extended end of the casing 64 and forms a sliding joint therewith limited by a set screw 66c, as shown in Fig. 3.

The collar member 65 is positioned inwardly from the end of the casing 64 and is provided with a plurality of radially extending lugs 65a. Each lug forms a loose joint with a jaw member 67 which extends from within

the casing 64 into the bore 66a of the knob 66. At the extended end of the knob 66, the bore 66a is provided with a plurality of notches 66b, each of which receives an offset end portion 67a of a clamp jaw 67 so as to form a fulcrum point therefor.

Each jaw member is provided with an inwardly sloping wedging portion 67b which constricts the space between the several jaw members, as shown in Fig. 3. A jaw release pin 68, having a conical inner end 68a adapted to register with the wedge portions 67b, extends between the jaw members. The pin 68 is spaced from the fulcrumed ends of the jaws 67 by a sleeve 69 secured to the extended end of the knob, as shown in Fig. 3. A spring 70 presses between the inner end of the stem and the collar 65 tending to force the conical portion 68a of the stem against the wedge portion 67b of the various jaw members, thereby forcing the ends of said jaw members so as to be held by the lugs 65a against the inner walls of the control rod

casing 64 and lock the movement of the knob 66 relative thereto. Inward movement of the pin 68 releases the several jaw members and permits the knob to be turned or shifted longitudinally so as to work the various clutches hereinbefore described.

Near the supported end of the boom 47, extending upwardly from the web 47c thereof, is a bifurcated lug 47h to which is secured the lower end of a supporting cable 71. The supporting cable 71 extends up from the lug 47h to the upper, inner side of the ironing board cabinet C, where it is secured to a suitable anchor 72.

The juncture of the supporting cable 71 with the boom 47 constitutes the fulcrum point so that downward movement of the extended end of the boom tends to raise the motor and casings 37 and 38. Thus the weight of the device is balanced.

When desiring to fold up the ironing board and cease using the apparatus, the iron 1 is removed from the yoke 61 and the boom and casing 37 rotated relative to the casing 38, and the fulcrum point of the lugs 47h, causing the cage 2 to drop in its guide members 1 until the apparatus is in the position shown by the dotted lines in Fig. 5. The ironing board can then be folded up in the usual manner and thereby conceal the apparatus from view.

In order to permit the boom to rotate relative to the casing and still permit unhindered movement of the cable 50, the casing 38 is provided with a relatively large arcuate slot 38b, as shown best in Figs. 10, 12 and 13.

The collar 17 is prevented from shifting due to the action of the sleeve 6 on the clutches 15 and 16 by screws which secure it to the casing 37, thereby keeping the controlling apparatus in the same position relative to the boom as said boom is rotated about the casing 38.

By turning the knob 66 in one direction or the other, the boom, together with the casing and mechanism therein, by reason of the traveler members 4 or 5, is caused to move in one direction or the other on the screw member 3 which is held stationary, causing the iron to shift transversely relative to the ironing board.

Pressing inwardly on the knob causes the iron to shift inwardly along the ironing board, and to pull out on the knob causes the reverse or outward movement of the iron. Thus the iron can be caused to move anywhere about the board desired by merely turning or pressing in or out on the knob 66.

When ironing pleats or ruffles where considerable intricate movement of the iron is necessary, the iron may be readily removed from the apparatus and these delicate operations performed by hand in the usual manner.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. The combination with a folding ironing board and a cabinet therefor, of an ironing apparatus comprising a boom extendable over said ironing board and foldable into said cabinet, a traveler member connected to said boom, an iron connected to said traveler member; mechanical means for shifting said traveler member longitudinally of said boom, and means for shifting said boom transversely relative to said ironing board.

2. The combination with an ironing board and a cabinet therefor, of a boom extendable over said ironing board and foldable into said cabinet, a traveler means, a mechanism for shifting said traveler means longitudinally relative to said boom, other mechanism for shifting said boom transversely to said ironing board, and an iron connected to said traveler member and shiftable longitudinally of and transversely to said ironing board with the movements of said traveler and boom.

3. The combination with an ironing board and a cabinet therefor, of a boom extendable over said ironing board and foldable into said cabinet, a traveler means, a mechanism for shifting said traveler means longitudinally relative to said boom, other mechanism for shifting said boom transversely to said iron board, an iron connected to said trav-

eler member and shiftable longitudinally of and transversely to said ironing board with the movements of said traveler and boom, and control mechanism for operating either 5 one or both of said shifting mechanisms.

4. In an apparatus of the class described, a boom means, a casing connected with the one end thereof, a support, traveler members connecting said casing with said support, a traveler means shiftable longitudinally of said boom, an iron connected to said traveler means, and mechanisms for shifting said traveler members and said traveler means.

5. In an apparatus of the class described, a boom means, a casing connected with the one end thereof, a support, traveler members connecting said casing with said support, a traveler means shiftable longitudinally of said boom, an iron connected with said traveler means, mechanisms for shifting said traveler member and said traveler means, and control means for causing said mechanism to operate either said traveler members or said traveler means, or both.

6. The combination with a folding ironing board and a cabinet therefor, of an ironing apparatus comprising a support mounted in said cabinet, traveler members shiftable transversely to said ironing board on said support, a casing mounted on said traveler member, a boom means extending from said casing over said ironing board, a traveler means shiftable longitudinally of said boom, mechanism mounted within said casing for shifting said traveler members, casing, and boom transversely to said ironing board, other mechanism mounted in said casing for shifting said traveler means longitudinally of said boom, and an iron connected with said traveler means.

7. The combination with a folding ironing board and a cabinet therefor, of an ironing apparatus comprising a support mounted in said cabinet, traveler members shiftable transversely to said ironing board on said support, a casing mounted on said traveler members, a boom means rotatable about the axis of said support and adapted to extend over said ironing board, a traveler means shiftable longitudinally of said boom, mechanism mounted within said casing for shifting said traveler member, casing, and boom transversely to said ironing board, other mechanism mounted in said casing for shifting said traveler means longitudinally of said boom, an iron connected with said traveler means, and a motor connected with said casing for driving said shifting mechanism.

8. The combination with a folding ironing board and a cabinet therefor, of an ironing apparatus comprising a support mounted in said cabinet, traveler member shiftable transversely to said ironing board on said support, a casing mounted on said traveler member, a boom means extending from said

casing over said ironing board, a traveler means shiftable longitudinally of said boom, mechanism mounted within said casing for shifting said traveler member, casing, and boom transversely to said ironing board, 70 other mechanism mounted in said casing for shifting said traveler means longitudinally of said boom, an iron connected with said traveler means, a motor connected with said casing for driving said shifting mechanism, 75 and control means for bringing said mechanism into operative relation with said motor.

9. The combination with a folding ironing board and a cabinet therefor, of a casing 80 mounted in said cabinet and shiftable transversely to said ironing board, a boom extending from said casing over said ironing board, said boom rotatable about said casing until within said cabinet, an iron connected with said boom and shiftable longitudinally thereof, mechanism for shifting said casing, and other mechanism for shifting said iron longitudinally of said boom.

10. The combination with a folding ironing board and a cabinet therefor, of a casing mounted in said cabinet and shiftable transversely to said ironing board, a boom extending from said casing over said ironing board, said boom being rotatable about said casing 95 until within said cabinet, an iron connected with said boom and shiftable longitudinally thereof, mechanism for shifting said casing, other mechanism for shifting said iron longitudinally of said boom, a motor means, and a 100 control means for connecting said motor with either one or both of said mechanisms.

11. The combination with a folding ironing board and a cabinet therefor, of a casing 105 mounted in said cabinet and shiftable transversely to said ironing board, a boom extending from said casing over said ironing board, said boom being rotatable about said casing until within said cabinet, an iron connected 110 with said boom and shiftable longitudinally thereof, mechanism for shifting said casing, comprising a screw member extending through said casing and mounted transversely to said cabinet, traveler members supporting said casing upon said screw member, and clutch means linking said traveler members with said motor, other mechanism for shifting said iron longitudinally of said boom, comprising means for moving said iron towards said casing, and other means for moving said iron away from said casing, and clutch means linking said first and second iron moving means with said motor.

12. The combination with a folding ironing board and a cabinet therefor, of a casing 125 mounted in said cabinet and shiftable transversely to said ironing board, a boom extending from said casing over said ironing board, said boom being rotatable about said casing until within said cabinet, an iron connected 130

- with said boom and shiftable longitudinally thereof, mechanism for shifting said casing, comprising a screw member extending through said casing and mounted transversely to said cabinet, traveler means supporting said casing upon said screw member, clutch means linking said traveler means with said motor, other mechanism for shifting said iron longitudinally of said boom, comprising means for moving said iron towards said casing, and other means for moving said iron away from said casing, clutch means linking said first and second iron moving means with said motor, and control means for connecting either one or both of said mechanisms with said motor.
13. The combination with an ironing board, a boom extendable over said ironing board, a traveler member connected to said boom, an iron connected to said traveler member, mechanical means for shifting said traveler member longitudinally of said boom, and means for shifting said boom transversely relative to said ironing board.
14. The combination with an ironing board, a boom extendable over said ironing board, a traveler member connected to said boom, an iron connected to said traveler member, means for shifting said traveler member longitudinally and transversely of said ironing board.

In testimony whereof, I have hereunto set my hand at San Diego, California this 1st day of July, 1929.
